HAND GRIP ATTACHMENT FOR A HOSPITAL-TYPE BED

Joseph M. Bertoldo, 627 Salem St., Malden 48, Mass.

Filed Nov. 30, 1962, Ser. No. 72,664

Term of patent 14 years

(Cl. D5—2)

FIG. 1

The dotted lines employed in FIGURE 1 are for illustrative purposes only.

I claim:

The ornamental design for a hand grip attachment for a hospital-type bed, substantially as shown and described.
